Joseph Shyer, Long Island City, N. Y., assignor to Zylo Ware Corporation, Long Island City, N. Y., a corporation of New York

Application June 7, 1946, Serial No. 130,488

Term of patent 3½ years

(Cl. D57—1)

To all whom it may concern:

Be it known that I, Joseph Shyer, a citizen of the United States of America, residing at Long Island City, New York, in the county of Queens, have invented a new, original, and ornamental Design for a Spectacle Frame, of which the following is a specification, reference being had to the accompanying drawing, forming part thereof.

Fig. 1 is a front view of a spectacle frame showing my design;

Fig. 2 is a side view of the same spectacle frame.

I claim:

The ornamental design for a spectacle frame, as shown.

JOSEPH SHYER.
